UNITED STATES PATENT OFFICE.

WILLIAM S. ATWOOD, OF MONTREAL, QUEBEC, CANADA.

BRAKE-CHAIN DRUM.

1,175,581.

Specification of Letters Patent. Patented Mar. 14, 1916.

Application filed November 9, 1914. Serial No. 871,053.

To all whom it may concern:

Be it known that I, WILLIAM S. ATWOOD, a citizen of the Dominion of Canada, and resident of the city of Montreal, in the Province of Quebec and Dominion of Canada, have invented certain new and useful Improvements in Brake-Chain Drums, of which the following is a full, clear, and exact description.

10 This invention relates to improvements in brake shaft chain drums, and the object is to provide a drum which may be inserted in a solid cast bracket without the necessity of leaving a great amount of play.

15 A further object is to provide a chain drum made in two parts, either one of which may be renewed independently of the other.

Various other objects and advantages will be apparent from the following description.

20 The device consists essentially of a drum divided intermediate its ends on a plane which intersects the axis of the drum at an angle other than 90 degrees. One of these parts carries a radial lug for the attachment of the brake chain.

25 Referring more particularly to the drawings:—Figure 1 is a front elevation of the drum in position in a solid cast bracket. Fig. 2 is a view similar to Fig. 1, illustrating 30 the method of inserting or removing the drum. Fig. 3 shows a slightly modified form of drum.

Referring more particularly to the drawings, 5 designates a solid cast brake shaft bracket, that is to say, a bracket formed with top and bottom apertures, and not with jaws or removable drum holding numbers. This bracket is provided with top and bottom apertures 6 and 7 for the reception of the ends 40 of the drum. The drum is composed of upper and lower parts 8 and 9, separated as shown at 10 on a plane which does not intersect the axis of the drum at an angle of 90 degrees. Each of the numbers may be provided with a flange 11, designed to hold the chain against jamming between the ends of the drum or bracket. One of the members, for example 8, is provided with a radially projecting lug 12 over which the end link of 45 the brake chain may be slipped and secured by a cotter or bolt passing through the aperture 13.

The drum is preferably designed for co-operation with a square brake shaft, and is 50 therefore provided with a square bore 14. The lower end of the drum is provided with

an aperture 15 for the insertion of a cotter pin or bolt to hold the drum to the shaft, and also to hold the same against creeping upward in the bracket, as will be readily understood from the drawing.

It will be noted that the distance between the outside faces of the flanges 11 is slightly less than the distance between the top and bottom of the bracket, so that the drum has 65 a certain up and down play in the bracket when not held by the pin 15', this play being equal to the space 16.

When it is desired to insert the drum the upper portion thereof is inserted in the upper part of the bracket and held with its flange 11 abutting the bracket, as clearly shown in Fig. 2. The lower part of the drum is then slipped into the lower part of the bracket in an angular position and 70 moved to vertical position in line with the upper portion. The upper portion is then dropped on the lower portion, the brake shaft 17 passed through both portions and secured by the pin 15', which also holds the 75 lower portion of the drum against riding up in the bracket.

In Fig. 3 a slightly alternative form is shown. It will be noted in Figs. 1 and 2 that the least length of the portion 8 is under the 80 lug 12, while in Fig. 3 the greatest length is under the lug 12. The reversal of the plane of separation thus permits the portions 8 to be made much smaller.

The advantages of this invention are obvious. The drum may be inserted in solid cast brackets as easily as in forked or other types of brackets. Most of the breakages which will occur will be in or near the lug 12, so that by dividing the drum it is possible 90 to replace a broken lug without the expense of replacing the entire drum. The parts of the drum will preferably be malleable castings, so that they may be made at no appreciable greater cost than the drums at 95 present in use, no machining being required at the line of separation between the two drum parts.

Having thus described my invention, what I claim is:—

1. A brake chain drum formed in two independently separable parts, separable intermediate the ends of the drum.

2. A brake chain drum formed in two independently separable parts, separable adjacent drum ends on a plane inclined with respect to the drum axis.

3. A brake chain drum formed in two parts of unequal length separating on a plane inclined with respect to the drum axis.
4. A brake chain drum formed of a plurality of tubular portions separately insertible in a holding bracket.
5. A brake chain drum formed of two tubular portions abutting one another in a plane inclined with respect to their axis, and adapted to be held in alinement by a brake shaft.
10. A brake chain drum formed in two parts of unequal length, and a brake chain attaching lug formed integral with the shorter part.
15. A brake chain drum formed in two parts abutting intermediate the drum ends, the abutting faces of said parts being formed to transmit rotary movement from one part to the other.
20. A brake chain drum formed of a plurality of tubular members abutting one another intermediate the drum ends, the abutting faces of said members being formed to transmit rotary motion from one member to the other, and a chain attaching lug carried by one of said parts.
25. In a brake chain drum, the combination
- with a square brake shaft of a chain drum, formed of a plurality of parts, each having a square bore for the reception of the brake shaft whereby said parts are held in alinement and against relative revolution.
10. In a brake chain drum, the combination with a brake shaft and a bracket of a chain drum formed of a plurality of parts abutting one another intermediate the drum ends and held axially in line by said brake shaft, the abutting faces of said parts being arranged to transmit rotary motion from one part to the other, and a chain attaching lug secured to one of said drum parts.
11. In a device of the character described, the combination with a bracket of a drum dividing intermediate its ends into two parts separating at such an angle that one of the parts may be moved radially and in a curved path relatively to the other during insertion in, or removal from the bracket.

In witness whereof, I have hereunto set my hand, in the presence of two witnesses.

WILLIAM S. ATWOOD.
